ADOLPH L. DE LEEUW, OF CINCINNATI, OHIO, ASSIGNOR TO THE CINCINNATI MILLING MACHINE COMPANY, OF OAKLEY, OHIO, A CORPORATION OF OHIO.

OILING SYSTEM.

1,102,186.

Specification of Letters Patent. Patented June 30, 1914.

Original application filed June 23, 1913, Serial No. 775,200. Divided and this application filed February 9, 1914. Serial No. 817,465.

To all whom it may concern:

Be it known that I, ADOLPH L. DE LEEUW, a citizen of the United States, and residing at Cincinnati, in the county of Hamilton and State of Ohio, have invented a new and Improved Oiling System, of which the following specification is a full disclosure.

This application is a division of my co-pending case No. 775,200 and this invention relates to a machine tool oiling system and it proposes a frame organization such that oil will be automatically elevated from a lower-most well or point to an uppermost reservoir or oil course, from which it will be gravimetrically distributed to the various bearings, either by means of conduits integral with the main casting or frame of the machine or by individual pipes leading from said oil course.

20 A primary object of this invention is to create a gravimetric oil distributing structure in which oil will be kept in continuous circulation through all of the wearing surfaces, and will be ultimately drained by gravity to an oil well, and then elevated against gravity to an uppermost distributing point, and then permitted to gravitate along appropriate channels to bearings arranged in a true ramification or parallel relation, 25 as distinguished from the usual multiple series, so that each bearing releases its contaminated oil directly to the well, and not to other bearings.

Heretofore an oiling system has been proposed in which oil was drawn from a well in the frame of the machine and then distributed to an uppermost bearing. Such small quantities of oil as passed through this bearing was released in a considerably contaminated condition by reason of the concentrated effect and in this state it was caused to pass through another bearing, which further contaminated it, and in turn released it into another bearing, and so on, until ultimately it was permitted to return to the oil well after having been successively contaminated by passing in sequence through several bearings. When it reached the oil well it was of course diluted by a larger mass of oil so that it was suitable for reapplication to the bearings. This system, while not injurious on the first reached bearing, was objectionable as to subsequent bearings, for

the reason that the latter received oil containing an undue percentage of impurity. 55 A drop of highly contaminated oil added to the well would be so diluted as to be harmless so that a drop taken from the well would represent good lubricating material, but as soon as this drop passed through the 60 first bearing it would be contaminated by a certain percentage of impure matter, the percentage of course being very much higher than before it passed through the bearing, i.e., much higher than the average value of 65 the bulk of oil in the well. To add this contaminated drop to the next bearing is bad practice, because of its increased contamination, and after it had passed through the second bearing it would be still further contaminated and even less fit for the third bearing, and so on.

The ramified construction proposed by this invention overcomes the above-mentioned objections, for the same quality of oil 75 is fed to each bearing, this quality being the average value of the bulk of oil in the well, and when the oil has been enriched with contamination by passing through the bearing it is discharged directly into the well, and 80 thus its impurities are greatly diluted before it reaches the next bearing by recirculation through the system.

Another object is to render available a simple frame design that will automatically 85 effect the oiling of the various bearings in the way aforesaid, without requiring an extensive built-up structure, and by enabling the major features to be produced by a simple casting process in the foundry. 90

Another object is to devise a milling machine frame that will especially provide for this system of oil distribution.

Other objects will be in part obvious from the annexed drawings and in part indicated 95 in connection therewith by the following analysis of this invention.

This invention accordingly consists in the features of construction, combination of parts, and in the unique relations of the 100 members and in the relative proportioning and disposition thereof; all as more completely outlined herein.

To enable others skilled in the art so fully to comprehend the underlying features 105 thereof that they may embody the same by

the numerous modifications in structure and relation contemplated by this invention, drawings depicting a preferred form have been annexed as a part of this disclosure, 5 and in such drawings, like characters of reference denote corresponding parts throughout all the views, of which:—

Figure 1 is a side elevation partly in section of a milling machine frame embodying 10 the oil distributing characteristics proposed by this invention. Fig. 2 is a detailed section taken through line 2—2 of Fig. 1, showing further details of the same. Fig. 3 is a side elevation partly in section of a milling 15 machine having a vertical spindle also embodying the features of this invention. Fig. 4 is a section through line 4—4 of Fig. 3, showing the internal construction of the frame.

20 Continuing now by way of a more detailed description, the construction of the horizontal spindle miller will first be described.

The frame consists of a base portion 1, from which rises a hollow column 2, which 25 preferably is a one-piece casting having guides 3 for the usual mounting of the knee, etc. At an appropriate point in the top of the column, a pocket 7 is formed by means of the side walls of the frame and a trans- 30 verse web 8 which is contoured to form the features to be hereinafter described. An oil-pipe 9 terminates in a vent which discharges into the pocket 7 at any suitable point thereof, for example from the exterior of the 35 frame, and this pipe enables oil to be forced up into said pocket in abundant quantities by an oil pump 10 mounted on the base of the machine and driven by a belt 11 and pulleys 12 and 13 from the main driving 40 shaft 14 of the machine.

Leading in opposite directions from the pocket 7 are shown two spill-ways 15 and 16 which are preferably crowned slightly, as shown by Fig. 2, to form gutters 17. At a 45 point slightly above the gutter 17 in one of its spill-ways, as for example in the spill-way 16, is a discharge aperture 18 from which leads an overflow pipe 19 directed toward the bottom of the column, and through 50 which the overflow or excess oil delivered by the pump will flow. The spill-way 15 and the gutter 17 thereof lead to a pocket 20 above the front bearing of the spindle, shown by the drawings as typical of a rotating 55 member such as a shaft, and an oil duct 21 permits the oil to drain to the wearing surfaces, and from the latter it flows ultimately to the oil well in the base. In like manner the spill way 16 drains into a pocket 22, 60 which, by means of a duct 23 similarly supplies the rear bearing of the shaft or spindle.

At a suitable point in the side of the frame is an opening 24, and bolted into this opening is a drive-unit 25 which as a matter of 65 convenience is separately manufactured as a

distinct structural entity and contains sun-dry gear-wheels and shafts constituting a power transmitting organization, and which is subsequently bolted in place to form a part of the main frame or column 2, and 70 thus conveniently provide the main frame with such supplementary shafts, gears and bearings as may be desired. This transmission unit provides extensions 26 and 27 that enter the interior of the column and the 75 upper surfaces of which are provided with canals 28 and 29 having suitable rifles for diverting oil and having suitable oil ducts 30 and 31 for feeding oil from the same to the bearing. These canals are supplied with 80 oil by means of pipes 32 and 33 that lead from pockets 22 and 20 and which are bent into position to bring their lower ends above the upper portions of the canals 28 and 29. Another gear insert unit is indicated by 34, 85 and in this instance, it constitutes a speed change organization, and it is supplied with oil preferably from the overflow pipe 19. The construction of these insert units will be further detailed in connection with the 90 vertical spindle machine. It may be noted, however, that the various shafts, gears, etc., which are additional or supplementary to the shaft or spindle above described, may in this way be assembled in final fixed 95 relation with the frame more accurately and more conveniently than by securing them directly to the frame, though they will be oiled equally well in either way by this system. After the oil has left the various 100 wearing surfaces aforesaid, it flows to the base of the machine and through an opening 36 to what may be termed an oil well 37 from which it is raised by the pump 10 as aforesaid. That is to say, the term "oil- 105 well" as used herein signifies the pocket or trap to which the oil gravitates ultimately and from which it is raised against gravity by the action of the pump. That is to say, the term "oil well" is descriptive of the 110 ultimate point of gravitation and is to be distinguished from the term "reservoir" which is indicative of a capacity for retaining a bulk of oil, so that the "well" may or may not exercise the functions of a reservoir, 115 depending upon its capacity or volume.

The vertical spindle organization is shown more clearly by Figs. 3 and 4, and will now be described. The column 40 of this machine rises from a suitable base 41 and terminates in a head 42 in which is journaled the vertical spindle 43 by means of bearings 44 and 45. At its upper end, an annular reservoir 46 is provided, which discharges the oil by means of an overflow 47 onto a 120 web 48 preferably cast integral with the frame. The oil is conveyed to the bearing 44 by means of the groove 49 leading from the annular reservoir 46, and it passes down the spindle to the lower bearing 45 from which 125

it is thrown off onto the main frame by the oil-ring 50, and it then flows down the incline 51 and ultimately to the oil well in the base. It is to be noted here that although in this instance the oil flows from the bearing 44 to the bearing 45, no undue contamination is experienced, since the bearing 44 carries hardly any load at all, it being relieved from thrust by the bearing 45. The web 48 is cast into a trough-like form having an upturned edge or lip 52 which inclines from the head 42 toward the rear end of the column, and suitably spaced are dams 53 and 54 that divert the oil sufficiently to cause it to flow down small drain pipes 55, 56 and 57. The drain 55 leads to the forward bearing 58 of a driving shaft 59, and the pipe 56 leads to the rear bearing of said shaft, and after the oil has passed through these bearings, it dribbles down the frame of the machine toward the base and into the oil well. This column, like that of the horizontal spindle, also has a similar opening 24 that receives a similar transmission unit 25 containing frame extensions 26 and 27 providing canals 28 and 29, from which lead ducts 31 and 32 to the various bearings of the transmission unit. Thus, the canal 28 provides a pool 60, into which oil is directly delivered by the pipe 57 and it then overflows the edge of the pool 60 and passes down the canal, being diverted at intervals by means of dams 61 and 62 to insure its flow through the ducts 31 to the various bearings, as shown by Fig. 35. 4. The oil overflowing the canals 28 and 29 and discharging from the various bearings then passes directly to the oil well in the base. Leading from a lower point of the web 48 is an overflow pipe 63 that discharges into the pool 64 of the speed change insert unit 34, and the oil then flows over the spill-way 65 and the successive dams 66 and 67, and finally through the discharge gutter 68 down through the well. Ducts or oil holes 69 lead to the various bearings of this unit, and the latter in turn discharge the contaminated oil to the central well, where it is diluted and returned to the system.

It will thus be perceived that this invention is well adapted to achieve the objects aforesaid in a simple and direct manner, and in a way preventing the admission of unduly contaminated oil onto any of the bearings. Without further elaboration, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed my invention, I claim as new and desire to secure by Letters Patent of the United States:—

1. A machine-tool oil-distributing organization of the nature disclosed combining a hollow frame having two horizontally aligned apertures forming spindle bearings, a spindle journaled horizontally in said bearings, said frame providing an oil vent elevated above the axis of said spindle and located between its ends and having a right and left oil-drainage into each of said bearings and also having an overflow located higher than said oil drainage, supplementary bearings receiving oil from said overflow, an oil-well at a lower portion of said frame, and a pump for elevating oil from said well to said oil vent. 70

2. A machine-tool oil-distributing organization of the nature disclosed combining a hollow frame having two horizontally aligned apertures forming spindle-bearings, a spindle journaled horizontally in said bearings, said frame being internally provided with an oil vent elevated above the axis of said spindle and having an oil-drainage into each of said bearings and also having an overflow for permitting the return of excess oil, supplementary bearings receiving oil from said overflow, an oil-well at a lower portion of said frame, and a pump for elevating oil from said well to said oil vent. 85

3. A machine-tool oil-distributing organization of the nature disclosed combining a hollow frame having two horizontally aligned apertures forming spindle-bearings, a spindle journaled horizontally in said bearings, said frame providing an oil vent elevated above the axis of said spindle and having an oil-drainage into each of said bearings, and also having an overflow located higher than said oil-drainage, supplementary bearings below said spindle, a pipe leading from said overflow and discharging oil on said bearings, an oil-well at a lower portion of said frame, and a pump for elevating oil from said well to said oil vent. 100

4. A machine-tool oil-distributing organization of the nature disclosed combining a hollow frame having two horizontally aligned apertures forming spindle-bearings, a spindle journaled horizontally in said bearings, said frame providing an oil vent elevated above the axis of said spindle and having an oil-drainage into each of said bearings and also having an overflow located higher than said oil-drainage, supplementary bearings receiving oil directly from said overflow, other bearings located between said spindle and said supplementary bearings and receiving oil independently thereof, an oil-well at a lower portion of said frame, and a pump for elevating oil from said well to said oil vent. 115

5. A machine-tool oil-distributing organi- 130

zation of the nature disclosed combining a hollow frame provided internally with a shelf-like oil-distributing canal arranged in an upper portion of the frame; a pipe extending upwardly from a lower point in said frame and terminating at an upper point thereof; a continuously driven pump for raising oil through said pipe whereby it may be continuously discharged into said 5 canal; a plurality of bearings mounted in said frame lower than said canal; a series of conduits leading from said canal at different points thereof, each conduit delivering oil directly to the bearings associated therewith, whereby each bearing will receive oil 10 in the state of purity delivered by said pump and uncontaminated by passage through a previous bearing; a lower portion of said frame being constructed to receive the oil 15 from all of said bearings and to divert the same to the lower end of said pipe.

6. A machine-tool oil-distributing organization of the nature disclosed combining a hollow frame provided internally with an elongated oil-trough extending in a substantially horizontal direction; a plurality of bearings arranged at different levels below said oil-trough; means embodying a pump for continuously withdrawing oil from a 20 point in said frame below said bearings and conveying the same upwardly against gravity and finally discharging said oil into said trough; a series of conduits independently leading from said trough to each of said 25 bearings; and means for permitting excess over-flow oil to escape into the lower portion of the frame; said lower portion being constructed to receive the oil draining from said bearings and to deliver the same to said 30 means embodying the pump.

7. A machine-tool oil-distributing organization of the nature disclosed combining a hollow frame internally provided with pockets such as 20 and 22 adapted to serve 35 as small oil-reservoirs; a plurality of bear-

ings arranged within said frame below said pockets; a conduit leading from each of said pockets and adapted to deliver oil therefrom to one of said bearings; means embodying a pump for continuously withdrawing oil 50 from a point below said bearings and conveying the same against gravity to an upper point relative to said frame; said frame being provided with means for receiving said oil and for delivering the same to said pockets and for permitting excess oil to overflow toward the lower portion of said frame; said lower portion being constructed to receive the oil draining from said bearings and to deliver the same to said means. 60

8. A machine-tool oil-distributing organization of the nature disclosed combining a hollow frame providing a shelf-like oil-distributing canal arranged in its upper part; a first bearing directly adjacent said canal, 65 said canal having an oil-duct opening through its wall and leading directly to said immediately adjacent bearing; a second bearing further removed from said canal and located lower than the same; a pipe 70 leading from said canal and adapted to deliver oil to said second bearing; means embodying a pump for continuously withdrawing oil from a point in said frame below said bearings and conveying the same upwardly against gravity and finally discharging said oil into said canal; a lower portion of said frame being constructed to receive the oil draining from said bearings and to direct the same to the said means; and 75 means whereby excess oil in said canal may escape to the lower part of said canal. 80

In witness whereof, I hereunto subscribe my name, as attested by the two subscribing witnesses.

ADOLPH L. DE LEEUW.
